RADIO BROADCAST SELECTING AND DISTRIBUTING SYSTEM

Filed Feb. 29, 1924

UNITED STATES PATENT OFFICE.

EDWARD E. CLEMENT, OF WASHINGTON, DISTRICT OF COLUMBIA, ASSIGNOR TO EDWARD F. COLLADAY, OF WASHINGTON, DISTRICT OF COLUMBIA.

RADIO BROADCAST SELECTING AND DISTRIBUTING SYSTEM.

Application filed February 29, 1924. Serial No. 696,076.

REISSUED

To all whom it may concern:

- Be it known that I, EDWARD E. CLEMENT, a citizen of the United States, residing at Washington, in the District of Columbia, have invented certain new and useful Improvements in Radio Broadcast Selecting and Distributing Systems, of which the following is a specification, reference being had therein to the accompanying drawings.
- 10 My invention relates to systems of radio broadcast distribution and is an improvement in the system described and claimed in my prior copending application, filed August 14, 1922, Serial No. 581,829.
- 14 The present invention has for its object to provide improved centralized means for receiving from primary or distant stations and relaying the same modulations to subscribers in a local area, or in other words, 20 an improvement in collecting and regional distribution. I attain my object by employing a superheterodyne receiving circuit, and retransmitting on the beat wave, for reception in the local area, this in combination 25 with simultaneous supervision, control, metering, etc., of the service thus rendered, over wired circuits to the subscribers' stations, all as in the aforesaid prior copending application. At each subscriber's station I locate a receiving set which may be fed with direct current over the subscriber's wired line circuit, and said receiving set may be of any desired type, provided the construction and adjustment of all the subscribers' sets is standard and uniform, so that 35 they are tuned once for all to the same wavelength, being the beat wave length transmitted from the local central station relay transmitter.
- 40 My invention is illustrated in the accompanying drawing, in which the figure is a diagram showing a central station, a subscriber's station and the line circuit interconnecting them.
- 45 Referring to the drawing C is a central station containing a telephone switchboard and a radio switchboard, each with connective apparatus and containing multiple line terminals for the subscriber's telephone line 50 16-17 which extends to the subscriber's station A, where a standard telephone instrument set is connected as shown. Tapped off from the wire 17 is a loop containing the windings of a relay L⁴ shunted by a condenser. This relay controls the normal con-
- nection of wires 52 and 53 to the line wires 16-17, and also controls the normal connection of a companion relay L⁵ to the line wire 16, which is the "tip" wire of the pair. The relay L⁵ in turn controls output terminals of the radio detector set 36^a, which are normally retracted so as to connect the set to the operator's receiving phone 36, which may be of any desired or suitable type. When the relay L⁵ is energized, it disconnects the subscriber's phone 36, and connects his radio set across the line 16-17, so that the operator at the radio switchboard can listen in over the line and ascertain if the central office beat wave is in tune with and is being properly received by the subscriber's instrument 36^a. The relay L⁵ is controlled by the radio switchboard operator by means of the key K₂, connected to the plug circuit P₂. When the plug of this circuit is inserted 70 in the subscriber's jack at x, a busy tone test is put on the multiple or test thimble of the line on the telephone switchboard, battery B is connected to the cut-off relay x', the operator's headset is bridged across the conductor 16-17, and finally key K₂ being closed, battery B throws current out on the tip side of the line 16 to energize relay L⁵ 75 and enable the operator to listen in on the subscriber's radio set. While I have shown the subscriber's receiving telephone cut off during this operation, it may remain connected, the cut-off being an additional feature which enables the central office to deprive the subscriber of all service in case 80 of necessity. When the operator is satisfied, and desires to be disconnected from the line the key K₂ is opened, and if desired the plug is pulled from the jack at x, the parts then all assuming their normal position 85 shown in the drawing when receiving may be continued at the subscriber's station in the ordinary way. Incoming telephone calls from the station A and outgoing calls resulting from telephone operators plugging in as at jack x², result in energizing relay L⁴, 90 which displaces relay L⁵ and totally disconnects the radio detector set 36^a from the line 16-17, this condition being maintained as long as the line is in use for conversation. 95
- Radio transmitter T comprises an antenna circuit 1, coupler 2, local oscillator circuit 3, the first detector 4, radio amplifying units 5 and 6, and a radiating circuit 7. Since the essential part of the heterodyning oper-

105

110

ation is in the elements 1, 2, 3, 4, it is to be understood that the arrangement of the amplifying and other stages between the first detector 4 and the radiating circuit 7 are subject to modification in accordance with good practice. The beat waves after being sufficiently amplified may be directly thrown upon the radiating circuit, or may be communicated through a modulator and 10 oscillator circuit, by which increased energy may be imparted to the radiating beat frequency waves. Ordinarily such energy may be communicated in sufficient quantity by the oscillator 3, the tubes 5 and 6 being 15 essentially power tubes and operating on any desired voltage.

The important point in the present invention is this: to select different stations and receive from any distant station at any wave 20 length or frequency, heterodyning by means of the local oscillator 3 with said incoming modulated waves, and by proper tuning of the oscillator circuit 3 always producing a standard beat wave to which the subscriber's 25 instruments in the local area are permanently tuned. The first and most important ancillary feature is that already described, of listening in from the central station by the radio operator over the subscriber's telephone line or other wired circuit, so as to 30 be able to properly adjust and tune the central office instrument to the subscriber's standard wave length.

I claim:

35 1. A broadcasting system comprising primary high power stations using different wave lengths, secondary stations having receiving radio sets tunable to the different primary wave lengths and also having relay 40 transmitting apparatus controlled by the receiving sets and operating on a standard fixed wave length the same for all secondary transmitter, and subscribers' receiving radio stations grouped around each secondary 45 transmitting station in its local area and tuned permanently to the fixed transmitting wave lengths thereof, the receiving radio sets at the secondary or relay stations each comprising a tuned circuit for receiving the

primary modulated waves, and a local oscillator circuit tunable to furnish heterodyning waves such that modulated beat waves will always be produced and fed into the transmitting circuit at the standard local frequency. 50

2. A radio system of intercommunication having a plurality of standardized uniform receiving stations divided into groups, all said stations being tuned to one common frequency and of sensitiveness limited to the areas covered by their respective groups, a local transmitting station for each group working on said common wave length, and means for modulating the waves radiated from said transmitting stations as determined by primary stations using variable wave lengths, said means comprising a primary circuit tunable to the wave lengths of the primary stations, and a local oscillator circuit tunable to furnish heterodyning 70 waves therefor, so as to always maintain the beat wave in the transmitting circuit at the common or standard wave length for the local group. 65

3. A broadcasting system comprising a primary station, a secondary distributing station, and a plurality of local receiving stations related to the secondary station and all in permanent tune therewith, means at said secondary station to receive broadcast 75 waves from the primary station at its wave length, and to relay and redistribute the same in its own area at the standard wave length to which its receiving stations are 80 tuned, and means also at said secondary station to determine when its transmitter is actually tuned to the fixed wave length of its receiving stations, said relaying means including a local oscillator tunable to furnish 85 waves at heterodyning frequencies for the modulated waves received from the primary 90 station or stations, with a constant beat frequency giving the standard wave length for local transmission. 95

In testimony whereof I hereunto affix my signature.

EDWARD E. CLEMENT.
